JAMES A. LANSING, OF SCRANTON, PENNSYLVANIA, ASSIGNOR TO SCRANTON STOVE WORKS, OF SCRANTON, PENNSYLVANIA, A CORPORATION OF PENNSYLVANIA.

COMBINED GAS AND COAL RANGE.

1,191,086.

Specification of Letters Patent.

Patented July 11, 1916.

Application filed May 1, 1916. Serial No. 94,765.

To all whom it may concern:

Be it known that I, JAMES A. LANSING, a citizen of the United States, residing at Scranton, in the county of Lackawanna and State of Pennsylvania, have invented certain new and useful Improvements in Combined Gas and Coal Ranges; and I do hereby declare the following to be a full, clear, and exact description of the same, reference 5 being had to the accompanying drawings, forming part of this specification.

This invention relates generally to improvements in combined gas and coal cooking ranges, and the particular object of the 15 invention is to provide a novel oven construction in which the oven may be readily heated with equal efficiency either by the combustion of gaseous or solid fuel. When heating the oven with solid fuel, the products 20 of combustion from the firebox must be conducted around the outside of the oven proper to prevent obnoxious gases from reaching the food within the oven, and, on the other hand, when heating with gaseous 25 fuel, the burner must be open to the interior of the oven and also to the atmosphere in order to obtain the draft sufficient to support combustion, and a proper heating effect within the oven. Thus the gas burner 30 chamber must be disposed beneath the oven and within the bottom portion of the flue for the gases coming from the coal firebox, and, since the gas burner chamber is necessarily isolated from the flue space in which 35 the chamber is positioned, it has been found that, when heating with solid fuel, a considerable portion of the oven remains cool, because of the inrush of outside air through the gaseous fuel chamber. The present invention 40 obviates this difficulty by the provision of a simple form of closure for shutting off the gas burner chamber from communication both with the interior of the oven and the atmosphere when using solid 45 fuel, thereby securing a dead air space, the air of which becomes heated uniformly with the air in the flue passage around the oven, so that the heating effect is distributed with equal efficiency over the entire effective area 50 of the oven.

Other objects of the invention are to generally improve the oven construction of a range of the type specified, as will appear from the ensuing detailed description of a

structural embodiment of the invention in a 55 preferred form.

The novel features of the invention will be particularly pointed out and specified in the claims at the end of the specification.

In the drawings:—Figure 1 is a front 60 elevation of a combined gas and coal range constructed in accordance with the present improvements, the front panel or wall of the range being removed to clearly illustrate the interior construction. Fig. 2 is a longitudinal horizontal sectional elevation of the same on the line 2—2 of Fig. 1. Fig. 3 is a longitudinal vertical sectional elevation on the line 3—3 of Fig. 2. Fig. 4 is a transverse vertical sectional elevation on the line 70 4—4 of Fig. 1.

Like characters of reference in the several figures indicate the same parts.

As shown in the accompanying drawings, the oven A is inclosed by the top outer wall 75 A', the side outer wall A², the bottom outer wall A³, the front outer wall A⁴ and the rear outer wall A⁵, all of said walls being formed of suitable panels and connected together in any preferred manner well known in the 80 art. The intermediate wall A⁶ separates the oven from the firebox B which may be of the usual construction adapted for the combustion of solid fuel. The top inner wall C, side inner wall C' and bottom inner wall C² 85 of the oven are spaced from the respective top side and bottom walls, A', A², A³, to form a continuous flue passage D for the circulation of the products of combustion from the solid fuel firebox B around the oven. 90 The heated air and products of combustion from the firebox B enter the flue passage D at the upper portion of said passage and pass around the side portion thereof between the side walls C', A² and under the inner bottom 95 wall C², the gases exhausting through a flue opening D' located in the rear wall A⁶ of the stove, between the upper and lower bottom walls of the oven.

The above described construction provides for the circulation of the heated air from the firebox all the way around the oven, when heating the latter with solid fuel, and at the same time the flue passage D is entirely isolated from the interior of the oven 100 so as to prevent any of the gases from the coal coming in contact with the food in the oven.

Within the space between the upper and lower bottom walls C^2 , A^3 of the oven is the gas burner chamber E , said chamber being isolated from the solid fuel flue passage by the outer vertical surrounding wall of a flue member E' , the upper open end of which communicates with the interior of the oven through an opening c in the upper bottom oven wall C^2 and the lower open end of which communicates with the outside atmosphere through an opening a in the lower bottom oven wall A^3 . It will be understood that the openings c and a register with the respective open ends of the flue member E' , thereby permitting the outside air to enter the oven A , under certain conditions which will be hereinafter more fully set forth. A gas burner E^2 of any suitable construction is positioned within the chamber E , the said gas burner being utilized when it is desired to heat the oven by burning gaseous fuel. In the chamber E and positioned below the opening c in the upper bottom wall C^2 of the oven is a seat, the latter being preferably formed at the upper end of an inner flue member E^3 somewhat less in height than the outer flue member E' .

In the preferred construction illustrated in the drawings, the outer flue member E' is formed of a single casting cylindrical or nearly cylindrical in shape and of an axial dimension sufficient to bridge the space between the upper and lower bottom walls of the oven, the said casting seating over the opening a in said lower wall and directly beneath the opening c in said upper wall. The inner flue member E^3 may also be constructed of a single casting adapted to be inclosed by the outer flue member E' . The surrounding wall of the inner flue member however slopes inwardly toward the top in order that the seat e at the top of the inner flue member may be somewhat less in diameter than the opening c in the upper bottom wall C^2 , so as to permit of a ready location of said seat from the interior of the oven.

An important feature of the invention consists in the provision of means for closing the opening between the gas burner chamber E and the oven and also the opening between said chamber E and the outside atmosphere, thus securing a dead air space in the gas burner chamber, when it is desired to heat the oven by the combustion of solid fuel. This dead air space prevents the outside air from reaching the upper or inner wall of the oven through the gas burner chamber, and thus, an even heating of the oven, when burning solid fuel, is insured. A simple way of carrying out this idea consists in providing a pair of cover plates F , F' , these being respectively of diameters to seat over the opening c in the inner bottom wall of the oven and the seat e at the top of the inner flue member F^3 . Preferably the

cover plates F , F' are connected by a suitable bolt f of the proper length to insure the cover plates seating over their respective openings, when applied. The wall of the oven surrounding opening c is preferably formed with a ledge c' and the upper cover plate F is of a diameter to lie flush with the upper surface of said oven wall, the cover plate being provided with a recess and lug formation f' whereby the pair of plates may be lifted out and applied by means of an ordinary stove plate lifter. In heating the oven with solid fuel, the plates will be applied, thus providing a dead air space in the gas burner chamber between the upper and lower plates, preventing the outside air from reaching the interior of the oven or the top plate F through the opening a . When it is desired to utilize the gas burner E^2 to heat the oven the plates will be removed, so as to permit the draft to blow the heat directly into the oven. The products of combustion from the gas burner pass out through a flue passage formed between an inner rear wall A^7 and the outer rear wall A^5 , the inner rear wall having a plurality of flue openings a^6 .

Mounted within the flue space between the walls C^2 , A^3 is a deflector plate H . This plate is positioned between the flue opening D' and the side portion of the flue, and connects the outer wall of the chamber E with the rear wall A^5 of the oven, so as to deflect the gases and heated air issuing from the lower end of the side portion of the flue D around in front of the chamber E before the air and gases can pass out the rear flue opening D' . Thus a complete circulation within the bottom flue space is insured.

What is claimed is:—

1. In a combined gas and coal range, a coal combustion chamber, an oven having upper and lower spaced bottom walls forming a flue for the circulation of gases from said coal combustion chamber, a flue passage connecting the space between said walls with the coal combustion chamber, a gas burner chamber within the space between said walls, said gas burner chamber composed of outer and inner flue members, the outer flue member bridging the space between the two bottom walls of the oven and the inner flue member having its upper end terminating below the upper bottom wall of the oven, both said flue members open at their upper and lower ends, openings in the upper and lower bottom walls of the oven adapted to register respectively with the open ends of the gas burner chamber, and a pair of connected cover plates adapted respectively to seat over the opening in the upper bottom wall of the oven and the upper end of said inner flue member.
2. In a combined gas and coal range, a coal combustion chamber, an oven having

- upper and lower spaced bottom walls forming a flue for the circulation of gases from said coal combustion chamber, a flue passage connecting the space between said walls 5 with the coal combustion chamber, a gas burner chamber within the space between said walls, composed of an outer flue member bridging the space between the two bottom walls of the oven and an inner conical 10 flue member having its upper end terminating below the upper bottom wall of the oven and provided with a seat, both said flue members open at their upper and lower ends, openings in the upper and lower bottom walls of the oven adapted to register 15 respectively with the open ends of the gas burner chamber, a seat formed in the upper bottom wall of the oven around the opening therein and a pair of connected cover plates adapted respectively to engage the seats in 20 said upper bottom wall and inner flue member.

JAMES A. LANSING.
